UNITED STATES PATENT OFFICE

DEZ ALBRITTON, OF SPOKANE, WASHINGTON, ASSIGNOR TO JOSEPH O. PARKER, OF SPOKANE, WASHINGTON

SCRATCH PAD DEVICE

Application filed May 8, 1931. Serial No. 535,924.

My invention relates to scratch pad devices and more particularly to a scratch pad device that is adapted to carry a roll of paper and is especially adapted for attachment to a telephone. Certain objects of the invention are to provide a scratch pad device of simple and inexpensive construction that is adapted to carry a large amount of paper in roll form. Further objects are to provide a scratch pad device that is readily attachable to phones of different types, that is very easy to manipulate, and which comprises means for retaining the paper smoothly in stretched form. Other objects are to provide simple means for installing the roll of paper, simple means for regulating the tension of the paper and novel guide means for the paper as it is fed through the device.

With the above and other objects in view which will appear as the description proceeds, the invention consists of the novel construction, adaptation, combination and arrangement of parts hereinafter described and claimed. These objects are accomplished by devices illustrated in the accompanying drawing; wherein:—

Figure 1 is a view in perspective of the device showing means for attaching same to the hand-set or French type of telephone wherein the ear and mouth pieces are both embodied in one member;

Fig. 2 is a view in longitudinal vertical section taken substantially on a broken line 2, 2 of Fig. 1;

Fig. 3 is a view in transverse vertical section taken on a broken line 3, 3 of Fig. 1;

Fig. 4 is an enlarged view in transverse section taken on a broken line 4, 4 of Fig. 1;

Fig. 5 is a fragmentary view partly in horizontal section and partly in plan showing the means for attaching the device to the ordinary desk telephone;

Fig. 6 is a fragmentary view in vertical section showing the means for attaching the device to a wall phone; and

Fig. 7 is a detail view in perspective of the clip member used in attaching the device to a wall phone.

Referring to the drawing throughout which like reference numerals indicate like

parts, the device comprises a casing having a solid slanting top 5 and V-shape side walls 6 integral with or fixed to said top. At the acute angles of said side walls the top is curved as at 7 and as most clearly shown in Fig. 2 of the drawing. Slightly above said curved portion a transverse bar 8 is pressed upwardly from the slanting metal top and a lug 9 is punched inwardly from the metal sides adjacent each end of said bar and bent upwardly in cooperative relation therewith. A similar bar 10 and lugs 11 are correspondingly formed for the uppermost end of said top and central lugs 12 are pressed upwardly from the metal of said top. A pencil clip or clasp 13 may be secured to a side of the casing. The sides of said casing may be provided with legs if desired whereby the device may rest and be used on a desk or other flat surface.

The paper 14 is rolled upon a spindle 15 having annular grooves 16 at its end portions. The larger end portions of the casing side walls 6 are provided with opposite slots 17 that are large enough to receive the ends of the spindle and have lower reduced portions that receive the annular end grooves of the spindle and serve as bearings therefor. The spindle is installed by springing the side walls of the casing outwardly, inserting its ends through the slots and letting the annular grooves drop down into the reduced ends of said slots as shown in Fig. 1 of the drawing.

After the spindle 15 is installed the paper 14 is pulled under and around the curved end 7 of the top 5 and is threaded under the bars 8 and 10 and lugs 12 which serve as guides therefor. The end of said paper may be pulled through the bar 10 and torn off along its edge as will be understood. Tension may be applied to the paper by bending the lugs 9 and 11 upwardly to press the paper against the transverse bars for the purpose of keeping same smooth and taut.

The device may be attached to the hand-set or French type of phone by means of a bracket arm 18 shown in Fig. 1. Referring to Fig. 5, the device may be attached to the ordinary desk type of phone, having an up-

right mouth-piece stand, by means of a semi-annular bracket clamp 19 pivotally riveted at 20 to one of the sides 6 of the casing, fitted around the stand, and secured on the other end by a thumb bolt 21. And the device may be mounted on a wall phone by providing the phone box with several vertical slots that are adapted to receive the flanges 22 provided on the sides of a clip member 23.

10 Notches 24 are provided in the top edge of said flanges where same join the clip member and said notches are adapted to receive the edge portions of the box at the top of said slots. The clip member is secured to

15 a side 6 of the casing by means of fingers 25 punched from the metal of said member, inserted into slots provided in the casing, and one of said fingers bent upwardly and the other bent downwardly whereby the clip

20 member is clamped to said casing as shown in Fig. 6. The lower end portions of said flanges are slanted or beveled, as at 26, which permits them to fit into slots of different lengths and at the same time provides means

25 whereby pressure on the device, such as caused when writing thereon, forces the device against the phone box and thus holds same securely in place.

Having thus described my invention, it being understood that minor changes may be resorted to in its construction and arrangement without departing from the scope and spirit of the invention, what I claim and desire to secure by Letters Patent of the United

35 States is: —

A scratch pad device having in combination a casing comprising a slanting top and V-shape sides joined thereto, a curved end portion for said top where same joins the sides at their acute angles, a spindle having a roll of paper mounted thereon, the ends of said spindle mounted in slots in the sides of the casing having lower reduced portions adapted to receive annular grooves in said spindle ends, a transverse bar punched upwardly from either end portion of the top whereby the paper may pass thereunder, lugs punched inwardly from the casing sides and bent upwardly whereby they are adapted to

40 cooperate with the transverse bars in engaging the paper and providing tension therefor, and central lugs for the top adapted to serve as guides for the edges of the paper.
